UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

ADDRESSING MACHINE.

Application filed April 21, 1924. Serial No. 707,860.

To all whom it may concern:

Be it known that I, JOSEPH S. DUNCAN, a citizen of the United States, residing at Chicago, in the county of Cook and State of Illinois, have invented certain new and useful Improvements in Addressing Machines, of which the following is a specification.

This invention relates to addressing machines and its object is broadly to provide means constantly operating with a platen and functioning with those address devices which are supplied with co-operating printing characters to make a printing impression of such character at the same time the address is printed upon an envelope or sheet and for various purposes.

An improved type of addressing machine is provided with means for feeding paper, envelopes, or the like in one direction and addressing devices in the opposite direction, the addressing devices bearing type characters and being successively brought into printing position under a reciprocating platen which is synchronized with the feeding means to address an envelope or a sheet of paper against the addressing device thereunder to make the printing impression upon the envelope or sheet. The printing or addressing devices are inked before reaching their printing position under the platen. More specifically my invention is intended for use in handling wrappers, or the like, which are to contain a number of articles and the character printed thereon in addition to the address is designed to show the number of articles to be contained in that individual wrapper. Of course, if only one article is to be wrapped this character may be omitted.

To this end my invention contemplates that the desired number or character appear on each printing device carrying an address, to which address more than one article is to be sent in the package, and this character or number is in addition to the address characters, and preferably located alongside thereof.

Furthermore, my invention contemplates the use of a platen which is elongated and provided at its elongated end with a ribbon which will be pressed by said elongated end against that portion of the envelope or sheet over the special printing character to make an impression of that character on the envelope or sheet. This extended end of the

platen and its ribbon will function whenever a printing device bearing a character in addition to the addressing characters comes into position thereunder.

In the accompanying drawings,

Fig. 1 is a plan view of a portion of an addressing machine of the type referred to and having my improvement thereon.

Fig. 2 is a sectional view on the line 2—2 of Fig. 1.

Fig. 3 is a sectional view showing my improvement and taken from the opposite side to that appearing in Fig. 2, and

Fig. 4 is a view of a printing device for use with my improvement.

Referring to the drawings, the numeral 1 designates the main frame of the addressing machine on which is mounted the rocking frame 2 which is pivoted to the main frame at 3 and which carries the platen 4 to make printing impressions on a sheet 6 from printing devices 7 which have been previously inked. Looking at Fig. 2, the sheet 6 is fed to the left and the plates 7 to the right. The platen frame 2 has a pair of rollers 8 mounted thereon to engage cams 9 on a shaft 10 journaled in the main frame. As the shaft 10 rotates, the platen frame with the platen thereon will be rocked to print the addresses on the paper 6. Also mounted on the shaft 10 is a third cam 11 and this cam bears 85 against the roller 12 on a rocker 13 pivoted on the main frame at 13'.

Also mounted on the frame 2 is a magazine 14 containing an inked ribbon 24. This magazine is conveniently made in two parts, the cover being pivoted as at 15 and being held in place by the spring 21. The inked ribbon 24 is stored in the magazine in folds, as shown in Fig. 2, and is looped around the platen and fed from the magazine to the platen and back thereto by means of rollers 16. These rollers are provided with intermeshing gears 17 whereby they operate in unison, and operating means therefor is provided in the form of a member 18 pivoted at 19 on the rocker 13 pivoted to the main frame at 13'. The member 18 is resiliently held in engagement with the teeth of one of the gears 17 by means of a spring 20.

One of the gears 17 is further provided with a knurled handle 22, whereby the rollers 16 may be actuated manually, if desired. It will be evident that the rotation of the

shaft 10 will cause actuation of the platen and also of the rocker 13. The movement of the rocker 13 is transmitted to the rollers 16 by means of the member 18 operating on the 5 teeth of one of the gears 17, the spring 20 permitting the end of said member 18 to ride over one gear tooth on its return movement, but preventing rotation of the gear in the reverse direction. Spring 23 acts on the 10 rocking platen frame 2 to hold the rollers 8 of said frame constantly against the cams 9.

The ribbon 24 is of comparatively narrow width, as shown in Figs. 1 and 4, and is designed to cover a designating character 25 15 of any suitable kind, on the printing devices, as shown in Fig. 4. Otherwise, the printing devices are of any suitable and usual construction. In operation, the platen frame 2 is rocked by means of the cams 9 and rollers 8 to make impressions on the sheet 6 from the printing devices or plates 7, and at the same time the ribbon 24 is fed through an aperture in the top of the magazine around the platen and back to the magazine, in a 20 series of intermittent movements, by the member 18 on the rocker 13, which in turn is actuated by the cam 11. Whenever the printing plate 7 carries a character 25, this character is impressed upon the sheet or envelope under the platen and on the opposite 25 side thereof than the impression from the other type on the plate. It should be noted that the ribbon is fed through a cam which is mounted on the shaft used to operate another part of the machine, as the platen, and therefore no additional operating means 30 is required.

From the above description it will be apparent that I have provided a simple but 40 efficient and easily provided mechanism for the purpose desired.

I am aware that changes in the form, construction and arrangement of parts may be made without departing from the spirit and 45 without sacrificing the advantages of the invention and I reserve the right to make all such changes as fairly fall within the scope of the following claims.

I claim:

50 1. In a device of the character described, a platen, a ribbon carried thereby, a common means to operate said platen and to feed said ribbon, and an additional means for feeding said ribbon.

55 2. In a device of the character described, a printing device having type thereon, means to print said type on a sheet, a designating character on said device, and additional means to print said character upon said 60 sheet.

65 3. In a device of the character described, a rocking frame, a ribbon magazine mounted thereon, means to feed said ribbon to and

from said magazine, and common means for actuating said frame and said feeding means.

4. In a device of the character described, a rocking frame, a ribbon magazine mounted thereon, means to feed said ribbon to and from said magazine, common means for actuating said frame and said feeding means, and manual means for feeding said ribbon.

5. In a device of the character described, a rocking frame, a ribbon magazine mounted thereon, means to feed said ribbon to and from said magazine, and means for preventing feeding of said ribbon in the wrong direction.

6. In a device of the character described, a rocking frame, a platen and an inking ribbon carried by said frame, and cam means to rock said frame and to feed said ribbon beneath said platen.

7. In a device of the character described, a rocking frame, a platen and an inking ribbon carried by said frame, and a single cam to rock said frame and to feed said ribbon beneath said platen.

8. In a device of the character described, a rocking frame, a platen and an inking ribbon carried by said frame, a single cam to rock said frame and to feed said ribbon beneath said platen, and tension means to hold said frame against said cam.

9. In a device of the character described, a rocking frame, a platen supported on said frame, an inking ribbon co-operating with said platen, a magazine on said frame to contain said ribbon and having a pair of apertures therein, and a roller disposed adjacent one of said apertures to engage said ribbon and feed it into said magazine.

10. In a device of the character described, a frame, a platen on said frame, a ribbon co-operating with said platen, a magazine for said ribbon supported on said frame, means to move said frame to actuate said platen, movement of said frame feeding said ribbon to and from said magazine.

11. In a device of the character described, a frame, a platen mounted on said frame, a ribbon cooperating with said platen, a magazine for holding said ribbon and supported on said frame, a pair of feeding rollers between which said ribbon passes, means to move said frame to actuate said platen, movement of said frame causing rotation of said rollers to feed said ribbon.

12. In a device of the character described, a printing device having type thereon, means to print said type on a sheet, a designating character on said device, and additional means to print said character upon said sheet, upon the opposite side thereof than the impression from the type.

JOSEPH S. DUNCAN.
